UNITED STATES PATENT OFFICE.

WALTER I. KIRK, OF CHICAGO, ILLINOIS, ASSIGNOR TO LYON & HEALY, OF CHICAGO, ILLINOIS, A CORPORATION OF ILLINOIS.

DESIGN FOR A STRINGED INSTRUMENT.

49,540.

Specification for Design.

Patented Aug. 22, 1916.

Application filed June 14, 1916. Serial No. 103,696. Term of patent 3½ years.

To all whom it may concern:

Be it known that I, WALTER I. KIRK, a citizen of the United States, residing at Chicago, in the county of Cook and State of Illinois, have invented a new, original, and ornamental Design for Stringed Instruments, of which the following is a specification, reference being had to the accompanying drawing, forming part thereof.

Figure 1 is a front view of a stringed instrument embodying my invention; Fig. 2 is a side view of the same.

I claim:

The ornamental design for a stringed instrument, as shown.

WALTER I. KIRK.
